UNITED STATES PATENT OFFICE.

MILLARD L. DUNHAM, OF NEW YORK, N. Y., ASSIGNOR OF ONE-FOURTH TO LOUIS DE F. MUNGER, OF NEW YORK, N. Y.

PISTON-RING.

1,241,836.

Specification of Letters Patent.

Patented Oct. 2, 1917.

Application filed April 18, 1916. Serial No. 91,856.

To all whom it may concern:

Be it known that I, MILLARD L. DUNHAM, a citizen of the United States and resident of the borough of Manhattan, in the city, county, and State of New York, have invented certain new and useful Improvements in Piston-Rings, of which the following is a specification.

This invention relates to piston rings, and 10 consists in a certain method of treatment, or step in the manufacture of piston rings, whereby these devices are rendered more efficient and serviceable in the performance of the functions for which they are de- 15 signed.

Piston rings are usually made from cast iron, and rely for their outward tension, whereby gas tight relationship with the cylinder wall is provided, upon the inherent 20 elasticity of the material from which cast, in the restorative effort toward resumption of their original contour; after the inward compression to which they must be subjected in order to introduce the rings, upon 25 a piston, within the cylinder. Thus the rings are usually cast or otherwise produced of a diameter greater than the inside diameter of the cylinder with which they are to be used, and are split at one point, by the 30 removal of a portion of the ring material, leaving two opposed ends, to provide space for the aforesaid inward compression; the space being of such extent only that when abridged by the inward compression for 35 service, the opposed ends will have spaced relationship just sufficient to serve the purposes of heat expansion and contraction in use.

Under this ordinary method of piston 40 ring manufacture the true circular form becomes distorted when the ring is contracted to fit within the cylinder; the distortion consisting in portions of the ring, near its ends, lagging inwardly, leaving clearances 45 between the outer peripheral surface of said portions—over certain arcs—and the opposed portions of the cylinder wall. These clearances permit sufficient leakage to affect the cylinder compression.

Various means have been sought to rectify this deficiency in piston rings, and my 50 present invention is directed to a novel, simple and efficacious method, whereby a circular ring, produced in the ordinary way, 55 is caused to have a true circular contour

after it has been contracted to fit within a cylinder.

This method, in brief, consists in first cutting a piece out of a cast ring, in the usual manner; leaving opposed, separated 60 ends; and then in spreading the mass of the ring material at its outer peripheral surface, in portions thereof adjacent to each of its opposed ends; to thereby give those portions, equally, an inherent, inward in- 65 clination; which constitutes, in the free state of the ring, a distortion thereof from a true circle; but which, in the contracted state of the ring, for service, gives it an absolutely true circular contour; whereby 70 the clearances before referred to as existing between the ring portions, near its ends, and the cylinder wall, are entirely filled.

Spreading the mass of the ring material, in its portions toward the ring ends, has the 75 effect of drawing the end portions of the ring inwardly, to give them equally a distorted contour, wherein the ends aforesaid are inclined inwardly, and said end portions caused to describe a segment of a cir- 80 cle whose diameter is slightly less than the diameter of the untreated portion of the ring in its free state.

This may be accomplished by punching 85 indentations in the outer peripheral surface of the ring, over longitudinal portions thereof including the ring ends and sections anterior thereto; the circumferential ring portions, thus defined, comprising the arcs referred to in which leakage clearances exist 90 under the present construction of ordinary piston rings.

The mass spreading, as by punching of 95 indentations aforesaid, has the effect of drawing inwardly the ring end portions, to thus slightly distort the ring in its free state; but causing it to have a true cylindrical contour when contracted in service. The stated result is achieved without de- 100 traction from the inherent elasticity of the ring material; the ring, after treatment, functioning as before; with the exception that, on account of its treatment, it is enabled to fit snugly within the cylinder all around its circumference, without leaving 105 any clearance spaces.

The reason for the above noted change in the contour of the ring is because of the mass displacement referred to; which, operating with the heel of the ring as a ful- 110

erum, as stated, draws inwardly the ring end portions, whereby the ring, when contracted, assumes a true cylindrical form.

Other features and advantages of my said 5 invention will hereinafter appear.

In the drawing:

Figure 1 is a plan view of a circular ring from which a section has been removed to permit contraction.

10 Fig. 2 is an edge view thereof, showing the method of forming indentations therein to spread the mass of the material.

Fig. 3 is a plan view, showing the effect of the mass spreading in changing the ring 15 contour at one side of the spacing.

Fig. 4 is a similar view, showing the ring as treated in Fig. 3, to fit within a cylinder.

Fig. 5 is an enlarged detail view, showing the ring as treated at both sides of the spacing and contracted to fit within a cylinder, 20 and

Fig. 6 is an edge view of the ring shown in Fig. 5.

In carrying out my improved method of 25 producing piston rings from circular castings of larger diameter, I remove a section from a metal annulus, as 1, leaving the opposed ends 2, 3, spaced apart sufficiently to allow the inherent elasticity of the ring 30 material, when the ring is fitted within a cylinder, to exert the desired degree of outward tension. The fault in this general form of ring construction, as now practised, is that while the diameter of the ring, in a 35 line drawn through its joint and heel, will remain practically unchanged when contracted, the side portions of the ring, near the joint, will then sag inwardly, when contracted, leaving at those points leakage 40 spaces between the ring and cylinder. This defect is remedied by me by distorting the ring from its circular condition shown in Fig. 1, through a certain treatment which results in causing the ring ends 2, 3, and 45 portions adjacent thereto, to incline inwardly, having the effect, when the ring is contracted, to bring its ends together, of then causing the ring to assume a true circular form.

50 Fig. 2 illustrates the character of the treatment applied, as that of punching indentations, as 4, in the outer peripheral surface of the ring, along restricted portions thereof lying between the ring ends and a medial line drawn across the ring, between its joint and heel.

Said indentations are produced by a tool 55 as 5, and serve to slightly spread the mass of the ring material at those portions, which

has the effect of giving the ring a permanent 60 distortion in its free state, as stated, which distortion enables the ring to assume an absolutely true circular form when contracted in service.

Reference to Fig. 3 will show one side 65 only of the ring as treated, the treated side 5^a, in the free state of the ring being distorted, while the opposite side 6 remains of circular form. In further illustration of the effect thus obtained, I have shown, in Fig. 4, 70 the partly treated ring of Fig. 3 as contracted and placed within a cylinder 7. It will there be seen that the treated portion of the ring, as contracted, fits perfectly within the cylinder 7, the opposite, untreated side 5 of 75 the ring appearing as distorted in the contracted state, whereby a clearance is seen to exist between said portion 6 and the cylinder wall. The efficacy of this treatment, as applied to both portions 5^a and 6 of the ring, 80 is clearly shown in Fig. 5, where the ring is seen to fit closely within the cylinder. Attention is directed to my co-pending application, Serial No. 91857, filed April 18, 1916, 85 for piston rings, said application referring to a piston ring capable of production under this application.

Variations may be resorted to within the spirit and scope of my claimed invention.

I claim:

1. The method of producing leak-proof 90 piston rings, consisting in removing a segment from a circular metal ring, and mechanically compressing said ring in its outer peripheral surface, at the end portions only 95 thereof, thereby effecting a mass displacement in said outer surface, to draw inwardly the free end portions of said ring, whereby said ring, when contracted for service, is of true circular form. 100

2. The method of producing leak-proof piston rings, consisting in removing a segment from a circular metal ring, and punching compressing depressions in its outer peripheral surface, at the end portions only 105 thereof, thereby effecting a mass displacement in said outer surface, to draw inwardly the free end portions of said ring, whereby said ring, when contracted in service, is of true circular form. 110

Signed at the borough of Manhattan in the city, county, and State of New York, this 14th day of April A. D. 1916.

MILLARD L. DUNHAM.
